UNITED STATES PATENT OFFICE.

ALEXANDER S. MACKENZIE, OF HOUSTON, TEXAS, ASSIGNOR TO CLAYTON GIN COMPRESS COMPANY, OF HOUSTON, TEXAS, A CORPORATION OF TEXAS.

FASTENER.

Application filed May 7, 1925. Serial No. 28,752.

This invention relates to temporary fastening means for securing wrappers about commodities which it is desirable to enclose within an envelope or wrapper, and as here disclosed, is shown in connection with the wrapping and temporarily securing of the burlap or fabric wrappers with which it is usual to envelop or wrap round bales of cotton.

An object of the invention is to provide a convenient and simple fastening means which may be attached to a wrapper, and, as the wrapper is fed through the press during the step of covering a bale, will temporarily hold the cover in snug condition about the bale ready for the permanent sewing or securing of the wrapper.

In the drawings:—

Fig. 1 is a view, somewhat diagrammatic, of a round bale press and a wrapper having an embodiment of the present invention applied thereto, partially wrapped around the completed bale.

Fig. 2 is a diagrammatic view showing the action of the fastener as it passes beneath the press roller.

Fig. 3 is a view in side elevation of the fastener on an enlarged scale, detached.

Fig. 4 is a view in plan of the under side of the fastener.

Fig. 5 is a view in side elevation of the fastener taken at an angle of 45° to Fig. 3.

Referring to the drawings in which like numerals indicate corresponding parts in the several views, 10 indicates generally a press of any desired type designed for forming a round bale from a suitable bat of cotton. The formed bale is shown at 11 with the cover 12 partially wrapped about the bale, said cover 12 being generally of burlap or other suitable fabric, and passing to the press in a continuous sheet from the wrapper roll 13, disposed in proper relation to the press.

The bale 11 will, of course, be formed in the usual manner by feeding the bat down the feed chute 14 to the rollers 15 of the press, and when the bale has been formed, the cover 12 will then be fed into the press, wrapped around the bale until it is brought to the overlapped position indicated at 16 in Fig. 2.

The continuous length of fabric coming

from the roll 13 will, of course, be severed at an appropriate point between the press and the roll 13, after the bale 11 has been completely wrapped and the ends of the cover have been brought to the overlapped position disclosed in Fig. 2.

In this position, the bale is completed, the cover has been applied, and the covered bale is ready to be removed from the press.

It is necessary, however, to temporarily secure the cover 12 at its lapped ends, in order that when the bale is removed from the press, the expansion of the highly resilient cotton will not displace the cover and distort the compressed and symmetrical bale.

In my present improvement, this is accomplished by the use of the temporary fastening device shown in detail in Figs. 3, 4 and 5.

The device, as there shown, comprises a fastener made up of the body member 17, which, as will be seen from Figs. 3, 4 and 5, is comparatively thin and of polygonal shape, being shown as square. The body has chamfered, tapered, or rounded portions 18 on its top side at each corner. The purpose of these chamfered portions 18 is to enable the fastener to pass easily between the surface of the press rollers 15 and the periphery of the bale without affecting the relation of the fastener to the cover 12. Extending from said body member at a point substantially at the center thereof is a shank 19, having a conical enlargement or end 20, which enlargement 20 is adapted to pierce the cover 12 and temporarily secure the overlapped ends of said cover together.

The base portion 21 of the conical enlargement has square sides as shown at 22, which sides are formed by grinding off the base of the cone. It will be noted that the sides 22 are arranged at an angle with respect to the sides of the body member 17, as clearly illustrated in Figs. 3, 4 and 5. It will be noted further that the sides 22 terminate at their meeting ends in sharp points or barbs 23 which engage and securely hold the threads of the cover and prevent the fastening device from being accidentally withdrawn from the cover 12 after it has been once forced through it. The base or under side of the conical enlargement presents a plane or flat surface to the

cover and is parallel to the under face of the body member 17.

In applying the fastener to the cover 12 as it is fed from the roll 13, the squared body member or portion 17 is, preferably, arranged in line with the weave of the cover, so that, when the fastener reaches the press roller 15, one of its sides will be positioned substantially parallel to the said roller.

10 While the body member is in line with the weave, it will be seen that the base of the conical enlargement, being diagonally arranged with respect to the body member, is also diagonal to the weave of the burlap, or 15 other cover material, and that the points or barbs 23 securely hold the threads and prevent the displacement of the fastener.

By the use of such a construction, it is extremely difficult to remove the temporary 20 fastener from the cover; in fact, the fastener cannot be accidentally removed from the overlapping ends of the cover as shown at 16, Fig. 2, after the roller 15 has once caused the enlargement to penetrate the 25 cover and be maintained in position therein by the engagement of the barbs with the threads.

I claim:

1. A fastener of the class described comprising a substantially flat body member having its exposed surface chamfered at the corners thereof, and a reduced shank extending from said body member and having an enlargement of substantially conical 35 form, the base of said enlargement being polygonal.

2. A fastener of the class described comprising a body member, and a shank extending from said body member having a 40 conical enlargement, the base of said enlargement being substantially square.

3. A fastener of the class described comprising a body member, and a shank extending from said body member having a

conical enlargement, the base of said enlargement having cut away sides. 45

4. A fastener of the class described comprising a flat polygonal-shaped body member having its exposed top surface rounded off at each corner, and a shank extending 50 from said body member and terminating in a conical enlargement, the base of said enlargement having straight sides arranged diagonally with respect to the sides of the body member.

5. A fastener of the class described comprising a body member of polygonal form, and a shank extending from said body member having an enlargement of conical form, the base of said enlargement having straight 60 sides arranged at an angle to the sides of said body member.

6. A fastener of the class described comprising a substantially square body member, and a shank extending from the body member and having an enlargement of conical form, the base of said enlargement being provided with straight sides, which are arranged at an angle to the sides of the body 65 member.

7. A fastener of the class described comprising a flat substantially square body member having chamfered corners, and a shank extending from said body member and having a conical enlargement, the base of 75 said enlargement having cut away sides arranged at an angle to the sides of said body member.

8. A fastener of the class described comprising a body member, and a shank extending from said body member having an enlargement of substantially conical form, said enlargement having a base provided with barbs. 80

In testimony whereof I have hereunto set 85 my hand.

ALEXANDER S. MACKENZIE.
